UNITED STATES PATENT OFFICE

EDWARD KIRBY BOTTLE, OF ELMIRA, NEW YORK, ASSIGNOR TO AMERICAN SALES BOOK COMPANY, LIMITED, OF TORONTO, CANADA, A CORPORATION OF ONTARIO, CANADA

MANIFOLDING BOOK

Application filed November 15, 1927. Serial No. 233,346.

This invention relates to sales books.

It is an object of this invention to provide a sales book which may be manipulated without soiling the fingers and which may be manufactured at a minimum of expense.

This invention accordingly comprises an article of manufacture possessing the features, properties, and the relation of elements which will be exemplified in the article hereinafter described and the scope of the application of which will be indicated in the claims.

For a fuller understanding of the nature and objects of the invention, reference should be had to the following detailed description taken in connection with the accompanying drawing, in which:

Fig. 1 is a perspective view of a sales book embodying this invention.

Fig. 2 is a similar view of a modification.

In the drawings of the first embodiment, the numeral 1 indicates a backing folded upon itself to form two backing sheets 2 and 3, the sheet 3 being longer than the sheet 2 to extend out from under it, as shown at 4.

To the free end of the backing sheet 2 is attached a pad of record leaves arranged in sets, each set comprising a leaf or sheet 5 bound within a stub 6 by an extension 7, 25 which is preferably separated from the record portion of the sheet by a weakened line 8. Each set also includes a free leaf or sheet 10 which is not bound within the stub, but which has its lower end attached to the lower

end of the sheet 5 by a weakened line 11. The sheets 5 and 10 are preferably formed of a single sheet having a weakened line near its center, and folded upon the weakened line to form the two leaves, but obviously it can be manufactured by pasting sheets together, if desired. The pad also preferably includes a carbon sheet 12 bound within the stub 6 and arranged to lie between the sheets 5 and 10.

In this embodiment, the book is a two-pad book having, on the extension 4 of sheet 3, the stub 14 of a second pad 15 whereby these leaves of the pad may be interleaved with the leaves of the first pad to form a triplicate record, as shown in the drawing. With such a

construction the transfer sheet 12 may be folded back upon itself in a manner similar to that of the record sheets to provide a bound transfer leaf 16 and a free transfer leaf 17. This enables the record to be copied on both the front and back surfaces of both the original sheet 10 and the triplicate 15, making a more legible copy upon the sheet 15 and making it difficult to alter the record upon the sheet 10 without detection.

In a book of this character, it is to be understood that, after inscription and after the removal of the record sheets of any set, the carbon strip will be found superposed upon the next set of record sheets, and the sheet 10 of this new set must be withdrawn from beneath the carbon and the free record sheet 10 and free transfer sheet 17 must both be raised to permit the insertion of the auxiliary sheet 15. In order to facilitate the performance of this operation both carbon sheets 16 and 17 are provided with thumb notches 18, 19 in position to expose a corner 20 of each free sheet 10 in succession. In order to facilitate the raising of the sheets 10 and 17 without soiling the fingers there is bound within the stub 6 a blocking strip 21, which not only serves to hold the staples of the pad in the customary manner, but also extends down below the upper end of the free transfer strip 17, so as to permit the grasping of the sheet 17 without the necessity of rubbing the finger upon the upper surface of the sheet 16. If desired, the upper free end of the sheet 17 may have the carbon removed therefrom, as shown at 22, on either one or both sides in order to serve as a carbon-free handle with which to manipulate the sheet. It will be understood, however, that soiling of the fingers occurs principally through the rather hard rubbing which occurs upon the upper surface of the transfer sheet 16 when the finger is rubbed across it to pick up a sheet, rather than in the light gripping which is sufficient to lift the sheet once it has been grasped. It is not of the same importance, therefore, to remove the carbon from the free end of the sheet 17 as it is to protect the fingers from the upper surface of the sheet 16.

It will be noticed that the weakened severance lines 8 of the sets of transfer leaves are positioned under the blocking strip 21 and forwardly in the book from the forward edges of the free leaves 10. This arrangement provides more space for manipulating the transfer sheet in changing it from one manifolding position to the next successive position.

10 It will be understood that, in the specific modification illustrated in Fig. 1 the upper sheet 17 which serves to make its impression upon the under side of the sheet 10 and upon the upper side of the sheet 15 may be dispensed with, if desired, since the record is transferred to the under side of the sheet 15 through the transfer material on the upper side of the sheet 16 and may readily be read through the sheet, if desired, a function 15 which is facilitated if the sheet 15 be made of translucent material.

20 In the event that the sheet 17 is dispensed with the blocking strip 21 will serve to permit the raising of the sheet 10 without rubbing the fingers upon the upper surface of the sheet 16. In either event, that is, whether the sheet 17 be dispensed with or not, the strip 21 may advantageously be extended below the upper end of the sheet 10. The strip 25 21 is, further, provided with a notch 23 corresponding to the notches 18 and 19 except that it will preferably be so arranged that no portion of the carbon sheet is exposed from beneath it at the notch.

25 In the particular embodiment illustrated in Fig. 2, a pad 30 of folded sheets is provided similar to the corresponding pad of the first modification, and having a single sheet of double-faced carbon 31, bound 30 within the pad. This modification differs, primarily, from that of Figure 1 in that the invention is here disclosed as applied to a book having only one pad. With this modification, the transfer material on the upper side of the carbon strip may be utilized either to transfer the impression to the under side of the free record sheet 32 to prevent tampering, or it may be used for making an additional record by means of an auxiliary sheet. 35 In either case, the blocking sheet 33 bound within the pad is arranged to extend, as shown at 34, below the free end 35 of the original record sheet 32, whereby the sheet may be raised without soiling the fingers.

40 45 By the above description it will be evident that the sales book may be manipulated without rubbing the fingers over the carbon surface and yet the book may be manufactured without the expense of removing the carbon material from the upper surface of the sheet. The blocking strip adds no material extra expense to the book, since it costs no more than the usual binding strip to hold the pad together.

50 55 Since certain changes may be made in the

above article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:—

1. A device of the character described comprising a plurality of sets of leaves bound into a pad, each set comprising a bound leaf and a free leaf, said bound leaf being attached to said free leaf at the end opposite the binding, a weakened line between said bound leaf and said binding, a transfer strip bound within said pad in position to extend between the leaves of each set in succession, a blocking strip bound within said pad above said transfer strip, said free leaves terminating at their upper ends below said binding and said blocking strip terminating at its lower end below the upper end of said free leaf, and a cut-out notch through said carbon strip and through said blocking strip in juxtaposition to said weakened line and in position to expose a corner of the free leaf of each of said sets in succession. 100

2. A device of the character described comprising a plurality of sets of leaves bound into a pad, each set comprising a bound leaf and a free leaf, said bound leaf being attached to said free leaf at the end opposite the binding, a weakened line between said bound leaf and said binding, a transfer strip bound within said pad in position to extend between the leaves of each set in succession, and a blocking strip bound within said pad above said transfer sheet, said blocking strip terminating at its lower end below the upper end of said free leaf and materially beyond said weakened line. 110

3. A manifolding book comprising, in combination, a plurality of sets of leaves bound together in a pad, each leaf comprising a bound leaf and a free leaf attached together at the edge of the bound leaf away from the binding, a carbon sheet bound within said pad comprising, also, a bound leaf and a free leaf similarly attached together, an auxiliary pad so mounted as to have its leaves adapted to be inserted successively between the bound and free leaves of each of said sets and a blocking sheet within said first-mentioned pad above the carbon sheet and of a length to extend beneath the upper end of said carbon sheet. 120 125

4. A manifolding book comprising, in com- 130

- bination, a plurality of sets of leaves bound together in a pad, each leaf comprising a bound leaf and a free leaf attached together at the edge of the bound leaf away from the binding, a carbon sheet bound within said pad comprising, also, a bound leaf and a free leaf similarly attached together, an auxiliary pad so mounted as to have its leaves adapted to be inserted successively between the bound and free leaves of each of said sets and a blocking sheet within said first-mentioned pad above the carbon and of a length to extend beneath the upper end of said carbon leaf and of said record sheet.
- 5 5. A manifolding book comprising, in combination, a plurality of sets of leaves bound together in a pad, each leaf comprising a bound leaf and a free leaf attached together at the edge of the bound leaf away from the binding, a carbon sheet bound within said pad comprising, also, a bound leaf and a free leaf similarly attached together, an auxiliary pad so mounted as to have its leaves adapted to be inserted successively between the bound and free leaves of each of said sets and a blocking sheet within said first-mentioned pad above the carbon sheet and of a length to extend beneath the upper end of said carbon sheet, the upper end of the free carbon sheet being devoid of carbon upon its under side.
- 10 6. A manifolding book comprising, in combination, a plurality of sets of leaves bound together in a pad, each leaf comprising a bound leaf and a free leaf attached together at the edge of the bound leaf away from the binding, a carbon sheet bound within said pad comprising, also, a bound leaf and a free leaf similarly attached together, an auxiliary pad so mounted as to have its leaves adapted to be inserted successively between the bound and free leaves of each of said sets, a blocking sheet within said first-mentioned pad above the carbon sheet and of a length to extend beneath the upper end of said carbon sheet, the upper end of the free carbon sheet being devoid of carbon upon its under side, and a cut-out notch through said carbon sheet and through said blocking strip in position to expose a corner of the free leaf of each of said sets in succession.
- 15 7. A manifolding book including, in combination, a plurality of sets of leaves bound into a pad having a stub, each set including a free leaf and a leaf bound into the stub of the pad, said bound leaf being attached to said free leaf at the end opposite the binding, a transfer sheet bound within said book in position to extend between the leaves of each set in succession, and a blocking strip bound within said stub above said transfer sheet, said blocking strip terminating at its lower end below the upper end of said free leaf, whereby the latter overlies said blocking strip which thus functions as a separator to sepa-
- rate the edge of the free leaf from the underlying transfer sheet so as to prevent soiling of the fingers while lifting said edge of the free leaf.
8. A manifolding book including, in combination, a plurality of sets of record leaves bound into a pad, each set including a bound leaf and a free leaf, said bound leaf being attached to said free leaf at the end opposite the binding, a transfer sheet bound within said pad in position to extend between the leaves of each set in succession, a weakened line between said bound leaf and said binding, and a blocking strip bound within said pad above said transfer sheet and terminating at its lower end materially beyond said weakened line.
- 70 9. A manifolding book including, in combination, a plurality of sets of leaves bound into a pad having a binding stub, each set including a free leaf and a leaf bound into said stub, said free leaf being attached to the bound leaf at the end of the latter opposite the bound end and being positioned in overlapping manifolding relation with said bound leaf, a transfer sheet bound within said stub in position to extend between the leaves of each said set in succession and having a backwardly lapped portion, an auxiliary pad so mounted that its leaves may be inserted successively in manifolding relation with said sets of leaves and said transfer sheets, and a blocking strip bound within said stub above said transfer sheet and terminating at its lower end below the upper end of said backwardly lapped portion of the transfer sheet, whereby said end of the transfer sheet overlaps said blocking strip, said overlapping end of the transfer sheet being free of transfer material on the under side thereof at said overlapping end portion.
- 75 10. A manifolding device including a plurality of sets of record leaves bound into a pad, each set including a plurality of leaves arranged in superposed manifolding relation one of which has a free end, said pad having a binding for said leaves, a transfer strip bound within said binding and terminating in a free end remote therefrom and positioned to extend between the leaves of each said set in succession, a separator strip bound in said binding and positioned above said transfer strip, said separator strip terminating at its lower end below said free end of the record leaf, said free leaf end, when said leaf is in writing position, overlying and contacting directly with said separator strip.
- 80 11. In testimony whereof I affix my signature.
